UNITED STATES PATENT OFFICE.

THOMAS F. SOMERS, OF NEW YORK, N. Y.

CORSET.

1,355,009.

Specification of Letters Patent.

Patented Oct. 5, 1920.

Application filed June 26, 1918, Serial No. 242,042. Renewed August 12, 1920. Serial No. 403,154.

To all whom it may concern:

Be it known that I, THOMAS F. SOMERS, a citizen of the United States, and residing at New York, in the county of New York and State of New York, have invented certain new and useful Improvements in Corsets, of which the following is a specification.

This invention relates to corsets and has particular reference to the construction of the body sections where the piping is formed to receive strengthening elements. It embodies a construction in which a folded reinforcing strip of fabric is secured to the outer wall of the piping by novel means presenting an attractive and ornamental appearance.

In the drawings,

Figure 1 is a plan view of a portion of a corset embodying my invention and Fig. 2 is an enlarged detail sectional view on the line 2—2 of Fig. 1.

The corset as shown in the drawings embodies the usual side members 10 and 11 provided with the usual hooks or eyes and in this instance I have shown an upper section 12 of elastic material. The main body portion is made up of overlapping sections 13, 14 and 15 of substantially non-elastic fabric. The main body portion is also provided with the usual elastic supporters 16, 17.

As shown in detail in Fig. 2 the adjacent sections such as 13 and 14 overlap the end 15 of the section 14 being folded in when the article is completed and the folded end resting above the inner free edge 16 of the section 13. Interposed between these ends is a strip of fabric 17 folded on itself with its free edges on the inside terminating in substantial coincidence with the ends of the parts 15 and 16. A row of stitches 18 extends through the infolded portion 15 of the section 14 at the extreme end where it is folded and those stitches pass through the

double thickness of the strip 17 and through the end 16 of the member 13 thereby securing the parts together. In this way the stitches do not show on the outer surface. A separate strip 19 is stitched at 20 and 21 to the under faces of the sections 13 and 14 on opposite sides of their overlapping portions, thus forming a piping which may receive a strengthening element to support the corset. The folded strip 17 may be made of any suitable fabric and of suitable color and the construction gives to the finished article an attractive appearance without being marred by an exposed seam.

I claim—

1. In a corset having a body made up of a plurality of overlapping sections, a piping construction at the meeting edges embodying an infolded edge of the outer section, an interposed folded strip and stitches passing through the infolded portion of the outer section, the folded strip and the inner section and a separate strip stitched to said sections on the inner side at its margin.

2. In a corset having a body made up of a plurality of sections, a piping construction at the meeting edges of said sections, the outer wall of which is composed of the free edge of one section, an overlapping and infolded edge of the other section and a folded strip interposed between said overlapping edges with its free edges on the inside and its folded edge extending beyond the infolded edge of said overlapping section, stitches passing through the free edge of said first mentioned section through both parts of the folded strip and through the infolded portion of said second mentioned section at the fold, and the inner wall of said piping being formed by a strip stitched to said sections at its margin on opposite sides of their overlapping edges.

In testimony whereof I affix my signature.

THOMAS F. SOMERS.
